HERBERT TALLEY, OF JOPLIN, MISSOURI, ASSIGNOR, BY MESNE ASSIGNMENTS, TO
HERCULES POWDER COMPANY, A CORPORATION OF DELAWARE.

SHELL-ASSEMBLING MACHINE.

1,105,937.

Specification of Letters Patent.

Patented Aug. 4, 1914.

Application filed April 24, 1912. Serial No. 692,933.

To all whom it may concern:

Be it known that I, HERBERT TALLEY, a citizen of the United States, residing at Joplin, county of Jasper, and State of Missouri, have invented certain new and useful Improvements in Shell-Assembling Machines, of which the following is a specification.

This invention relates to shell assembling machines.

10 Explosive gelatin dynamite is put up in paper cartridges or shells. This operation, which was formerly carried on by hand, may now be carried on automatically by different types of machines which are adapted to fill 15 a relatively large number of shells grouped and held in a shell holding shuttle whose receptacles or pockets are usually arranged in a more or less regular or symmetrical manner. Formerly the shells have been placed 20 in the shuttles by hand, but latterly this has been done by a machine, and it is to that type of machine that the present invention relates.

The present invention is set forth in my 25 application on shell filling and closing machines, Serial No. 691,825, filed April 19, 1912, as it is well adapted for use in connection with the machine and the automatic motive fluid pressure operating system.

30 thereof disclosed in the said application, but the present machine constitutes an independent invention in various respects, among which are the construction and manner of coöperation of the mechanisms thereof 35 by which the shells are first arranged in rows and then in units, whether these mechanisms be operated by motive fluid pressure, hand, or other means, and in another respect, the invention is independent, *i. e.*, in the 40 arrangement and coöperation of motive fluid pressure means for the parts thereof and, still further, means for controlling the motive fluid pressure means.

The invention has for its objects the provision 45 of a shell assembling machine which will be adapted to accurately position and assemble the shells in proper relation for transfer into the corresponding receptacles or pockets of the shuttle; second, to provide 50 new means for pushing or delivering the shells thus assembled into the shuttle when the latter is in position to receive them; third, to provide novel means for assembling the shells without possibility of denting or injuring them; fourth, to provide novel means

for passing the assembled shells from the machine to the shuttle without danger of injury to the shells; fifth, to provide novel operating means for the mechanisms of the machine, particularly, operating means arranged to form an interlock so as to prevent premature operation of any parts which would result in damage to the shells or to the machine; sixth, to provide new motive fluid pressure controlling means for the assembling and delivering mechanisms.

The invention consists in the provision of new means, individual and coöperative, for carrying out the several objects above enumerated as well as others not specifically set forth but which will presently appear.

In the accompanying drawings:—Figure 1 is a longitudinal section, certain parts being in full lines; Fig. 2, a horizontal section, certain parts being in full lines; Fig. 3, a cross section, certain parts being in full lines; Fig. 4, a detail view showing how one of the pusher pins engages and moves a shell; Fig. 5, a detail perspective view of one of the division plates; Fig. 6, a similar view of the carriage; and Fig. 7, a diagram of the fluid pressure means, valves and pipe connections for controlling and operating the shell assembling mechanism.

At 27 there is shown in a diagrammatic manner, a shell holder or shuttle to illustrate the use of the present invention which is designed to place the paper shells or cartridges in the shuttle. Any type of shell holding shuttle 27 may be employed. As generally constructed, these shuttles are provided with parallel rows of shell holding pockets or receptacles. The present machine is adapted to assemble as many shells as there are shell holding pockets in the shuttle and to position them exactly in the relationship of the pockets so that when the shuttle is in proper position, the assembled shells may be introduced by the machine into the shuttle.

The operative mechanisms of the machine are supported by a frame 1^b. Surmounting the frame 1^b is an elongated guide frame 80 having tracks 81 extending lengthwise thereof and parallel to each other. Mounted 100 to travel on these tracks by sliding thereon or by the use of rollers, is a carriage 82 which is provided with shelves 83 corresponding in number to the number of rows of shell-holding pockets or receptacles in 110

the shell holding shuttle 27 and adapted to support rows of shells which are to be inserted in the pockets of the respective rows of the shuttle. Leading to these shelves 83 are inclined guides 84 corresponding in number thereto whose extremities 85 are more nearly parallel to the shelves 83 than are the guides 84. The parts 85 being nearly horizontal, do not tend to dent or crush the shells when coming in contact with them and they direct them to the guides 84, which, due to their greater inclination, more rapidly direct paper shells to the shelves 83, as will presently appear. The shelves 83, 10 inclined guides 84 and parts 85 are arranged in two parallel sets above the tracks 81, there being a space between the said sets for the accommodation of the vertically extending agitators and division plates 86. 15 The carriage 82 carries serpentine or other suitable cam tracks 87 on which the lower ends of the division plates 86 rest, legs 88 having rollers 89 being preferably provided for this purpose. The shell holding hopper 20 90 which contains the shells 91 is arranged so that the outlet 92 receives the upper ends of the division plates 86. The parts being in this position, the shells 91 naturally fall in superposed position between the division 25 plates 86, but to prevent any crowding or inequality of positioning, the division plates 86 are arranged to vibrate up and down as the carriage 82 moves to and fro. The shells are supported at their ends by the lower 30 part of frame 82, as shown in Fig. 1.

Slidably mounted on the frame 1^b so as to move at right angles to the carriage 82 is another carriage 93 which carries the pusher pins 94 corresponding in number to 35 the shell-holding receptacles or pockets in the shuttle 27. The free ends of these pusher pins 94 are pointed at 95, there being provided a shoulder 96 which is of a proper size to engage the edge of the shell at its 40 mouth after the pointed end 95 has entered the shell. The pointed ends 95 insure the engagement of the pusher pins with the shells without likelihood of damaging the latter, the pointed construction permitting 45 the end of the pin to easily enter the mouth of the shell and the shoulder 96 effecting the pushing of the shells into the shuttle 27 from between the division plates 86 and off of the shelves 83. A cylinder 97 carried by 50 frame 1^b and a piston 98 therein which has a piston rod 99 connected to carriage 82, affords means for causing the carriage 82 to play to and fro. A cylinder 100 secured to frame 1^b has a piston 101 and piston rod 55 102 connected to the frame 93, whereby the frame 93 and the pusher pins 94 are made to move to and fro. The compressed air is admitted to cylinder 97 through pipe 103, in turn automatically controlled, as will presently appear. Compressed air is ad-

mitted to cylinder 100 by pipe 104 and automatically controlled in a manner hereinafter set forth. At the lower end (Fig. 7) of the cylinder 97 two by-pass pipes 105 and 106 connect that cylinder with the right hand 70 end (Fig. 7) of cylinder 100. Assuming that the shell holding shuttle 27 is in position for the placing therein of the shells 91, and that they have dropped into the spaces between the division plates 86, the 75 carriages 82 and 93 being in retracted position as shown in Figs. 1 and 2. When pressure is supplied through pipe 103 to cylinder 97, it forces the piston 98 to the lower end (Fig. 7) of the cylinder. This movement is not abrupt, due to the provision of an oil check 150 embodying a piston in a cylinder containing oil, the piston being connected to the carriage 82 and having a loose fit in the cylinder, allowing the oil to 80 gradually flow or leak past it as the piston moves. The carriage 82 by its travel, causes the receiving parts 85 to enter under the shells between the division plates 86, without injury to the shells, the shells being let 85 down the inclined guides 84 until they eventually rest upon the shelves 83 in a position lower than that in which they formerly reposed. When the shelves 83 are arranged crosswise of the division plates 86, 90 the shells are assembled or classified in a manner corresponding to the shell holding pockets or receptacles in the shuttle 27 and they are exactly in line with those pockets and ready to be pushed into them. The disposition of the shelves 83 crosswise of the division plates 86 occurs when the piston 98 has passed beyond the point where the pipe 105 enters cylinder 97, and as soon as this 95 occurs the pressure from pipe 103 passes via pipe 105 into the cylinder 100, immediately forcing the piston 101 to the left-hand end of the cylinder 100 (Fig. 7) carrying with it the frame 93 and the pusher pins 94 whose points 95 first enter the shells and whose shoulders then push the shells into 100 the pockets or receptacles in the shuttle 27. An oil check 151, similar to oil check 150, prevents abrupt movement of frame 93. As 110 will presently appear, following this operation, the controlling mechanism may open the pipe 103 to exhaust and pressure may be admitted to pipe 104 to force the piston 101 back to its normal position, whereupon the pressure entering through pipe 104 enters 115 pipe 106 and forces piston 98 back to its normal position.

The shell assembling mechanisms of the present machine may be operated other than by the use of compressed air and in so far as 120 the construction and co-operation of those mechanisms are concerned, they constitute an invention by themselves, but I prefer to operate these mechanisms by the use of the cylinders 97 and 100 and their pistons which 125 130

constitute another part of the present invention and, while different controlling means for said cylinders might be employed, I prefer to use the controlling valves and mechanism shown in diagrammatic Fig. 7, which constitute a part of the controlling system set forth in my application Serial No. 691825, filed April 19, 1912, on shell filling and closing machines. At 107 is disclosed a four-way pilot valve. Air pressure from any suitable source is supplied to the valve casing by a pipe 108; 109 is an exhaust branch for the valve. At 110 is shown a controlling cylinder, one end of which has a pipe connection 111 with the four-way valve 107 and the opposite end a pipe connection 112 with the said valve 107. Any suitable means, such as a lever 113 carried by valve 107, may be employed for turning it. At 116 is a four-way master valve which is operated by a piston 117 in cylinder 110. 137 is a pipe connecting the master valve to the cylinder 97; 104 is a pipe connecting the cylinder 100 to the pipe 131 leading to the master valve 116. At 133 is shown a valve which permits a quick introduction of pressure through pipe 104 to cylinder 100 or a slow exhaust therefrom. At 132 is a pressure checking valve which momentarily cuts down the pressure introduced via pipe 137 into cylinder 97. When the pilot valve 107 is in one position, it admits the pressure from pipe 108 through pipe 111 to cylinder 110, thereupon throwing master valve 116 to a position where the pressure will pass through pipes 131, and 104, into cylinder 100, whereupon piston 101 will position the pusher pins 94 and their carriage 93 in retracted position. The pressure will then also flow via pipe 106 into cylinder 97 and force back the piston therein, retracting the carriage 82. The pressure back of the piston in cylinder 97 will also exhaust through pipes 103, 137, valve 132, master valve 116, and exhaust pipe 128. When thus arranged, the parts are in their normal positions. If now, the pilot valve 107 be turned a quadrant's distance, pressure will flow from pipe 108 into pipe 112 and into cylinder 110, forcing the piston therein to the other end of the cylinder and turning the master valve 116 a quadrant's distance, whereupon pipe 108 will be placed in communication with pipe 137, the pressure meanwhile being checked at 132. The pressure will flow from pipe 137 into cylinder 97, forcing the piston 98 to the lower end (Fig. 7) of cylinder 97 and pushing the carriage 82 to the other end of its track, thereby causing the shelves 83 to subdivide the rows of shells 91. Immediately this occurs, however, the piston 98 permits the pressure from cylinder 97 to flow via pipe 105 into cylinder 100 and thereupon forces the piston 101 to the far end of the cylinder 100, but before this action has

taken place, the pipes 104 and 131, have permitted the pressure in cylinder 100 to exhaust through master valve 116 and branch 128 so that there is no opposition to the advance of the piston 101. Immediately the piston 101 advances, the pusher pins 94 cause their tips 95 to center in the shells 91 and the shoulders 96 then engage the mouths of the shells and push the latter into the pockets in the shuttle 27. On turning the valve 107 back to its former position, the parts will be restored to normal position and an empty shuttle 27 can then be brought into position for filling. Immediately the carriage 82 is back in normal position, additional shells 91 drop down between the division plates 86 so that another batch of shells may be immediately assembled and placed in the empty shuttle.

Having thus described my invention, what I claim as new and desire to secure by Letters Patent, is:—

1. In a shell assembling machine, the combination with division plates for arranging the shells in separated rows, of division shelves for separating the respective shells of the different rows from each other while said rows are stationary.

2. In a shell assembling machine, the combination with division members for arranging the shells in separated rows, of division members for separating the respective shells of the different rows from each other, said sets of division members being adapted for movement in general crosswise relation to each other without displacement of the shells from their initial row arrangement, whereby the shells may be first assembled in rows and the shells of the respective rows then separated from each other when in their initial row arrangement and position.

3. In a shell assembling machine, the combination with division members adapted to assemble the shells in rows arranged substantially vertically, the shells in each row being horizontal and touching each other, of a plurality of shelves, the members of which are adapted to space or separate the individual shells of the respective rows and to support them while the rows of shells remain in their initial arrangement and position.

4. In a shell assembling machine, the combination with division members adapted to assemble the shells in rows arranged substantially vertically, of a plurality of shelves, the members of which are adapted to space or separate the individual shells of the respective rows and to support them, the set of division members and the set of shelves being adapted for relative movement crosswise of each other, whereby the shelves enter sidewise between the shells without displacement of the latter when the shells are in their initial arrangement.

5. In a shell assembling machine, the combination with means for arranging the shells in rows, and shell supporting means adapted for relative crosswise movement to the shells 5 to separate the individual shells of the respective rows when said rows are in initial position, of shell displacing or ejecting means movable crosswise in relation to the means aforesaid and adapted to act on the 10 shells when they are in their initial row position.
6. In a shell assembling machine, the combination with a plurality of upright division members adapted to arrange the shells in 15 upright rows, of a plurality of shelves adapted for movement in general crosswise relation to the shells between the division members and to subdivide the rows of shells and support them, and a plurality of pusher pins 20 arranged to move in the shell holding cells or spaces defined by the division members and shelves in the direction of the length of the shells adapted for ejecting the shells from the cells.
- 25 7. In a machine for assembling shells, the combination with means for initially arranging the shells in assembled and spaced relation in the positions they will assume when in the shell holding devices of a shell holding shuttle, of a plurality of movably mounted pusher pins adapted to displace the assembled shells while they are thus initially assembled and spaced, so that they may be delivered directly into a shell holding shuttle from initially assembled position.
- 30 8. In a machine for assembling shells, the combination with means for initially arranging the shells in assembled and spaced relation corresponding to the relative positions they will assume when in the shell holding devices of a shell holding shuttle, of means for thereafter delivering the assembled shells directly into the shuttle.
- 35 9. In a machine for assembling shells, the combination with means for arranging the shells in rows, of a plurality of movably mounted shelves having inclined guides adapted to enter between the shells of the respective rows and space and direct them 40 to the shelves.
- 45 10. In a machine for assembling shells, the combination with means for arranging the shells in rows, of a plurality of movably mounted shelves having inclined guides adapted to enter between the shells of the 50 respective rows and space and direct them to the shelves, and means adapted to engage the shells and push them from the shelves, whereby they may be delivered to a shell holding shuttle.
- 55 11. In a shell assembling machine, the combination with a shell holding hopper, of movable division members arranged so that the shells in the hopper may enter between 60 them, means for separating or spacing the

individual shells when the shells are in rows between the division members, and means for moving the division members during the movement of said shell separating or spacing means.

70 12. In a shell assembling machine, the combination with a shell holding hopper, of movable division members arranged so that the shells in the hopper may enter between them, means for separating or spacing the respective shells when the shells are in rows between the division members, and means operated by the shell separating or spacing means adapted for moving the division members during the movement of said shell separating means.

75 13. In a shell assembling machine, the combination with a hopper adapted to contain the shells, of reciprocatable division members arranged so that the shells may enter therebetween from the hopper to thereby dispose the shells in rows, a carriage, shell separating shelves carried by the carriage which are adapted to enter between and to support the respective shells of the rows 80 aforesaid, and means on the carriage adapted to reciprocate the division members during the movement of the carriage.

85 14. In a shell assembling machine, the combination with a hopper adapted to contain the shells, of reciprocatable division members arranged so that the shells may enter therebetween from the hopper to thereby dispose the shells in rows, a carriage, shell separating shelves carried by the carriage 90 which are adapted to enter between and to support the respective shells of the rows aforesaid, means on the carriage adapted to reciprocate the division members during the movement of the carriage, and a plurality 95 of pusher pins positioned to engage the ends of the shells and adapted for pushing the shells out of their assembled position, whereby they may be delivered directly into a shell holding shuttle.

100 15. In a shell assembling machine, the combination with means for assembling the shells, of a plurality of pusher pins corresponding in number to the shells intended to be shifted and having reduced ends adapted to enter the mouths of the shells and provided with parts adapted, respectively, to abut the ends of the shells, said pins being arranged and adapted to push the assembled shells out of position.

115 16. In a shell assembling machine, the combination with fluid pressure operated means for initially assembling the shells in the spaced condition corresponding to that assumed by them in a shell holder, of other fluid pressure operated means for displacing the assembled shells for delivery to a shell holding shuttle.

120 17. In a shell assembling machine, the combination with fluid pressure operated 130

- means for initially assembling the shells in the spaced condition corresponding to that assumed by them in a shell holder, of other fluid pressure operated means for displacing the assembled shells for delivery to a shell holding shuttle, and means adapted to cause the operation of the fluid pressure operated shell displacing means subsequent to the initial assembling of the shells.
18. In a shell assembling machine, the combination with fluid pressure operated means for assembling the shells in the spaced condition corresponding to that assumed by them in a shell holder, of other fluid pressure operated means for displacing the assembled shells for delivery to a shell holding shuttle, and means controlled by the fluid pressure operated means of the assembling means which regulates the action of the fluid pressure operated means of the shell displacing means aforesaid.
19. In a shell assembling machine, the combination with means for assembling the shells in the spaced condition corresponding to that assumed by them in a shell holder, of other means for displacing the assembled and spaced shells whereby they may be delivered to a shell holding shuttle, actuating means for the shell assembling means, other actuating means for the shell displacing means, and means for controlling the actuating means of the shell displacing means by the actuating means of the shell assembling means.

20. In a shell assembling machine, the combination with shell assembling means, of a cylinder and piston for operating said means, shell displacing means whereby the shells may be delivered to a shell holding shuttle, a piston and cylinder for operating the shell displacing means, by-pass fluid pressure connections between the cylinder of the shell assembling means and the cylinder of the shell displacing means, whereby the pistons of the respective cylinders respectively control each other's movements due to by-passing of the fluid pressure, and means for admitting fluid pressure to, and exhausting it from, said cylinders.
21. In a shell assembling machine, the combination with means for initially arranging the shells in rows, of means for separating the shells of the rows while they remain in their initial row arrangement and position.
22. In a shell assembling machine, the combination with means for initially arranging the shells in rows, of means for separating the shells of the rows while they remain in their initial row arrangement and position, and means for thereafter displacing the assembled shells.

In testimony whereof, I hereunto affix my signature in presence of two witnesses.

HERBERT TALLEY.
